(57) **CLAIM**

The ornamental design for a cam lock, as shown and described.

DESCRIPTION

FIG. 1 is a perspective view of a cam lock showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an operational perspective view of the cam lock in FIG. 1 when a cover is open;

FIG. 9 is an operational left view of the cam lock in FIG. 1 when a cover is open; and,

FIG. 10 is an operational top view of the cam lock in FIG. 1 when a cover is open.

The broken line showing is included for the purpose of illustrating and forms no part of the claimed design.
